The ornamental design for a display screen or a portion thereof with graphical user interface, as shown and described.

DESCRIPTION

The FIGURE is a front view of a display screen or a portion thereof with graphical user interface according to our design. The broken lines showing portions of the display screen or a portion thereof with graphical user interface are included for the purpose of illustrating portions of the article and form no part of the claimed design. The dash-dot lines indicate a boundary or perimeter of the graphical user interface and form no part of the claimed design. In the figures, the perimeters of the portion of the underlying display screen and the graphical user interface are understood to be flush. The areas including stipple-fill represent areas having a different appearance.
